DESIGN FOR A FABRIC

Max Semaria, Brooklyn, N. Y.

Application May 26, 1933. Serial No. 48,218

Term of patent 3½ years

To all whom it may concern:

Be it known that I, MAX SEMARIA, a citizen of the United States, residing at Brooklyn, in the county of Kings and State of New York, have invented a new, original, and ornamental Design for a Fabric, of which the following is a specification, reference being had to the accompanying drawing, forming part thereof.

The figure is a plan view of a fabric, showing my new design, which comprises elements of playing cards in association with groups or sets of parallel lines, which are shown as black in the drawing, but which are colored in the print and

are preferably green; but they may also be otherwise colored.

It will be understood that the elements of the playing cards which are shown in the design may also be colored differently than as shown in the drawing.

The drawing is shaded to show color and contrasting effects.

I claim:

The ornamental design for a fabric as shown and described.

MAX SEMARIA.
